J. D. JENKINS.
CARBURETED AIR LAMP.

No. 73,900.

Patented Jan. 28, 1868.

Jesse D. Jenkins

UNITED STATES PATENT OFFICE.

JAMES D. JENKINS, OF CHARLESTOWN, MASSACHUSETTS.

IMPROVED CARBURETED-AIR LAMP.

Specification forming part of Letters Patent No. 73,900, dated January 28, 1868.

To all whom it may concern:

Be it known that I, J. D. JENKINS, of Charlestown, in the county of Middlesex and State of Massachusetts, have invented a Safety Vapor-Lamp; and I do hereby declare that the following is a full and exact description thereof, reference being had to the accompanying drawings, and to the letters of reference marked thereon.

The nature of my invention consists in combining within the body of a lamp a quantity of material (that will readily absorb fluid) saturated with naphtha, and also a fan-blower that will throw a steady blast of air through said saturated material.

I am aware that portable gas-machines have been made in which air has been made to pass through saturated material; but in all such cases the air-propelling arrangement acted irregularly or intermittently, thus requiring some kind of pressure-regulator, which necessarily added in the bulk of the machine; but I do not think any one has yet been devised in which a blast is blown through by a fan-wheel, and securing, as I do, a steady flow of carbureted air without the intervention of a pressure-regulator.

To enable others skilled in the art to make and use my invention, I will proceed to describe its construction and use, reference being had to the accompanying drawings and the letters of reference marked thereon.

In the drawings, Figure 1 represents a vertical section of my improved lamp. Fig. 2 is a perspective view of the same.

A is a base containing the clock-work G H, and a small centrifugal fan-blower, I.

L L' is a tube leading from the fan-blower up into the chamber C, opening in the lower part, so as to deliver the air (sent in by the blower) into the saturated material M.

M is a mass of cotton, tow, wool, asbestos, or other suitable material, saturated with naphtha or some kindred fluid, covered by a wire-gauze diaphragm, N N.

E is a gas-cock, and D a burner, made in any of the usual forms for hydrocarbon-vapor burners.

F is a plug used for drawing off any surplus fluid.

To prepare my lamp for burning I first fill it by removing the burner D and pouring in a sufficient quantity of naphtha to just saturate the packing M. The surplus, if there be any, is to be drawn off through the plug F. The burner and plug is then replaced and the clock-work G H wound up. If now the gas-cock E is opened, the fan-blower I will throw a current of air through the saturated packing M, and thence, having become carbureted in its passage, it will pass through the burner D and then burn, giving a steady, beautiful light.

The advantages that I claim for my improved lamp are that, as it contains no fluid except that held by the packing, there can be no explosion, and that I get a very superior light at a very low cost.

Having thus described my invention, I will proceed to set forth my claim.

What I claim as my invention, and desire to secure by Letters Patent, is—

As a new article of manufacture, a lamp in which the vapor for burning is produced by sending a current of air through a saturated packing, said current being impelled by a fan-blower, substantially as and for the purpose set forth.

JAMES D. JENKINS.
